UNITED STATES PATENT OFFICE

EMIL A. BEYL, OF MINNEAPOLIS, MINNESOTA

VENTILATOR

Application filed August 1, 1930. Serial No. 472,263.

This invention has for its object to provide an extremely simple and highly efficient ventilator for buildings, stacks, vents and the like, and to this end, it consists of the novel 5 devices and combinations of devices herein-after described and defined in the claims.

In the accompanying drawings, which illustrate the invention, like characters indicate like parts throughout the several views.

10 Referring to the drawings:

Fig. 1 is a front elevation of the improved ventilator and a fragment of the stack on which it is mounted;

15 Fig. 2 is a view partly in plan and partly in horizontal section taken substantially on the line 2—2 of Fig. 1;

Fig. 3 is a view partly in side elevation and partly in vertical section taken on the line 3—3 of Fig. 1; and

20 Fig. 4 is a fragmentary view principally in section taken on the line 4—4 of Fig. 3.

The numeral 5 indicates a stack on which the improved ventilator is mounted and within said stack and rigidly secured thereto are 25 two spiders 6 vertically spaced the one above the other. A pivot shaft 7 axially aligned with the stack 5 is carried by the two spiders 6, has screw-threaded engagement with the lower one and extends through a bearing 30 therefore in the upper one. This pivot shaft 7 extends materially above the upper end of the stack 5.

The improved ventilator is in the form of a sheet metal right-angle elbow having a diameter slightly greater than that of the stack 5 and its open lower end is telescoped slightly over the upper end of said stack out of contact therewith so as to shed water and prevent the same from running down on the inside of said stack.

35 The ventilator is loosely supported on the upper end of the shaft 7 to freely swing about the axis of said shaft under the action of the wind. Said shaft 7 at its upper end is rounded and extends into a seat 9 therefore in the under side of a cast metal saddle 10. This saddle 10 in cross-section is of concavo-convex formation with its concave side uppermost and substantially concentric with the open 40 upper end of the elbow 8. Said saddle 10

has on its outer end a depending segmental body 11 which fits against the inner side of the vertical section of the elbow 8 and is rigidly secured thereto. The saddle 10 is further secured to its body 11 by a reinforcing rib 12 integral with said body and rib. The elbow 8 is held in a true upright position on the shaft 7 by a spider 13, similar to the spiders 6, rigidly secured to said elbow below the body 11 and has a bearing that is 55 turnable on said shaft.

A collar 14 on the shaft 7 above the spider 13 affords a stop for said spider to prevent the elbow 8 from being lifted in respect to the shaft 7 sufficiently to unseat the saddle 10 60 from said shaft.

65 Mounted on the saddle 10 is a nozzle 15 which projects into the elbow 8 from its back toward the center of its open upper end. This nozzle 15 is of relatively large diameter 70 and slightly forwardly contracted. The saddle 10 holds the nozzle 15 in a slightly rearwardly inclined position so as to drain outside of the elbow 8 and with its projected axis at the center of the outer end of said elbow. 75 The intake end of the nozzle 15 projects outward of the elbow 8.

80 The delivery end of the nozzle 15 is slightly forward of the saddle 10 and its lower portion is depressed to form an open pocket 16 for collecting condensation or rain that may be driven by the wind into said nozzle. The pocket 16 engages the inner end of the saddle 10 as a stop during the assembling of the nozzle 15 and saddle 10 and properly positions 85 said nozzle on the saddle 10. To prevent rain from being driven completely through the nozzle 15 there is formed on the outer edge of the pocket 16 an upstanding flange 17. Leading from the bottom of the pocket 16 to the exterior of the elbow 8 is a drain 18. This drain 18 projects through the elbow 8 outward thereof just above the spider 13 and below the open front end of said elbow. 90 Any rain or condensation collecting in the pocket 16 will be carried by the drain 18 to the exterior of the ventilator.

95 Within the nozzle 15 and extending from the top to the bottom thereof is a plurality of laterally spaced collector plates 19. These 100

collector plates 19 will collect any condensation within the nozzle 15 rearward of the pocket 16 or rain driven thereagainst and convey the same to the bottom of said nozzle 5 where the same escapes to the exterior of the ventilator. The open delivery end of the elbow 8 is outwardly curved or expanded, as indicated at 20, so that any condensation or water collecting therein or moisture from 10 the outside will be caused to drip outside of the ventilator.

Projecting outward from the open delivery end of the elbow 8 is a weather vane 21 formed from a single sheet of metal set vertically edgewise at the horizontal center of 15 said end of the elbow 8. This vane 21 is bifurcated to receive the delivery end portion of the elbow 8 and the prongs formed by this bifurcation at their inner edges are turned 20 laterally to afford flanges 22 having the same contour as the underlying portions of the elbow 8 and are riveted or otherwise rigidly secured thereto to hold the vane 21 in position on the ventilator. The vane 21 is further secured to the elbow 8 by a pair of brace 25 rods 23 anchored to the elbow 8 at diametrically opposite sides and attached to opposite sides of the vane 21.

The above described ventilator provides a 30 simple and efficient method of using the wind velocity to assist the natural draft in a ventilating or smoke flue to increase the efficiency thereof. The mounting of the ventilator on the top of a stack for free swinging 35 movement about the axis of the pivot shaft and equipping the same with a weather vane to always keep the elbow with its back to the wind and wind in blowing over and around the elbow will create a siphon action 40 in the flue. Furthermore, the wind in passing through the nozzle 15 will further increase this siphon action in the flue.

The saddle 10 and its body 11 in addition to supporting the nozzle 15 perform another 45 important function in that they serve as a counter-weight to overcome the horizontal section of the elbow 8 and the weather vane 21 and hold the ventilator balanced about the axis of the shaft 7 so as to freely rotate without undue friction.

What I claim is:

1. The combination with a stack, of an elbow 55 mounted on the stack to swing about the axis thereof, a weather vane on the elbow at the outer open end thereof, a saddle in the elbow, and a nozzle extending into the elbow from the back thereof and mounted on the saddle, said saddle serving as a counter-weight for holding the elbow balanced about the axis around which it swings.

2. The combination with a stack having a 60 pivot shaft, of an elbow, a weather vane on the elbow at the open outer end thereof, a saddle in the elbow provided with a bearing seat which rests on the upper end of the shaft

and loosely supports the elbow thereon with freedom to swing about the axis of the stack, and a nozzle extending into the elbow from the back thereof and mounted on the saddle, said saddle serving as a counter-weight for holding the elbow balanced about the axis of the shaft on which it is free to turn. 70

3. The combination with a stack, of an elbow mounted on the stack to swing about the axis thereof, a nozzle extending into the elbow from the back thereof, and a plurality of laterally spaced upright collector plates in the nozzle which extends substantially the full length thereof. 75

4. The combination with a stack, of an elbow mounted on the stack to swing about the axis thereof, a nozzle extending into the elbow from the back thereof, and an upright collector plate in the nozzle, which extends substantially the full length thereof. 80

5. The combination with a stack having a pivot shaft, of an elbow, a saddle directly and rigidly secured to the elbow, said saddle having a bearing seat which rests on the upper end of the shaft and loosely supports the elbow therefrom with freedom to swing about the axis of the stack, and a nozzle mounted on the saddle and extending through the elbow at the back thereof. 90

6. The combination with a stack, of an elbow 95 mounted on the stack to swing about the axis thereof, a nozzle extending into the elbow from the back thereof, said nozzle being rearwardly inclined to drain through the back of the elbow, said nozzle having near its inner end a circumferentially extended moisture collecting pocket, and a downwardly and forwardly inclined drain pipe leading from the drain pocket through the bottom of the nozzle. 100

In testimony whereof I affix my signature.
EMIL A. BEYL.
